(57) **CLAIM**

The ornamental design for a drywall board with tapered edges as shown.

DESCRIPTION

FIG. 1 is a top perspective view of a drywall board with tapered edges showing my design;

FIG. 2 is a bottom perspective view of the design of FIG. 1;

FIG. 3 is a left view of the design of FIG. 1;

FIG. 4 is a front view of the design of FIG. 1;

FIG. 5 is a right view of the design of FIG. 1;

FIG. 6 is a back view of the design of FIG. 1;

FIG. 7 is a top view of the design of FIG. 1; and,

FIG. 8 is a bottom view of the design of FIG. 1.

1 Claim, 5 Drawing Sheets
